HIGH CHAIR ATTACHMENT

Henry J. Wiele, 401 Vernon Ave., West Burlington, Iowa, assignor of one-fourth to H. Charles Ephraim and one-fourth to Richard C. Wynne and John A. Kinken,
Washington, D.C., a partnership

Filed Dec. 21, 1959, Ser. No. 58,735

Term of patent 14 years

I claim:

The ornamental design for a high chair attachment, as shown and described.
